UNITED STATES PATENT OFFICE.

WILLIAM M. EVENSEN, OF CHICAGO, ILLINOIS, ASSIGNOR TO GOSS PRINTING PRESS COMPANY, A CORPORATION OF ILLINOIS.

PRINTING-PLATE CLAMP.

1,344,939.

Specification of Letters Patent. Patented June 29, 1920.

Application filed November 6, 1917. Serial No. 200,502.

To all whom it may concern:

Be it known that I, WILLIAM M. EVENSEN, a citizen of the United States, residing at Chicago, county of Cook, and State of Illinois, have invented certain new and useful Improvements in Printing-Plate Clamps, of which the following is a specification.

The invention relates to adjustable plate clamps, such as are used in positioning and holding in position electrotype, stereotype and other plates upon the cylinder or other form bearing member of a printing press.

The invention consists in the novel articles, parts, constructions, arrangements, combinations and improvements herein shown and described.

The objects and advantages of the invention will be set forth in part herein-after, and in part will be obvious herefrom, or may be learned by practice with the invention; the same being realized and attained through the means, instrumentalities and combinations pointed out in the appended claims.

25 The accompanying drawings, referred to herein and constituting a part hereof, illustrate one embodiment of the invention, and together with the description serve to illustrate the principles thereof.

30 Of the drawings:

Figure 1 is a side elevation of a plate clamp embodying the invention, and showing sectional fragments of the plate and of the press bed;

35 Fig. 2 is a transverse section of the clamp and press bed on line 2—2 of Fig. 1 looking in the direction of the arrows;

Fig. 3 is a bottom plan of the clamp alone;

40 Fig. 4 is an end elevation of the device alone, looking at it from the left as shown in Fig. 1;

Fig. 5 is an isometric view of one of the clamping members;

45 Fig. 6 is a view of the main clamping screw and

Fig. 7 is a view of the auxiliary clamping screw.

Referring to the accompanying drawings, illustrating by way of example the present preferred embodiment of my invention, the clamping plate or jaw 1 is provided with a beveled, undercut edge 2, adapted to take over the beveled edge of the plate 3 to position and firmly hold down

the plates upon the plate bed 4 of a cylinder or other like press member.

The clamp is adapted to work in slots of different cross-sectional forms in the bed 4, but as illustrated, the slots 5 are formed with opposing straight walls 6 and 7, which are parallel to each other, the bottom part of the groove, however, being undercut as shown at 8 and 9.

The body 10 of the clamp is fixed to, or integral with, the clamping jaw 1, and is of general rectangular form, substantially filling the portion of slot in the press bed having the parallel side walls, the clamp body extending downwardly past the portion of the slot wherein the walls are undercut (Figs. 1, 3 and 4). As embodied, the clamp body is integral for its entire length within the slot, but is recessed intermediate or centrally of its length to receive co-operating expanding members 14 and 15, which are forced outwardly into the undercut portions at the sides of the slot to hold the clamp in position against the printing plate.

In accordance with one feature of the invention, the co-operating expanding members and the clamp body are so formed that the clamp is self contained, that is, it has no loose part but holds together when handled. As embodied, a recess 16 is formed transversely through the bottom part of the body 10 of the clamp and intermediate of the ends of the clamp body. This recess has the side walls 17 and 18 thereof undercut and preferably beveled divergently upwardly. The two co-operating expanding members 14 and 15 are substantially of half the width of the body 10 of the clamp (see Fig. 3). Each of these members 14 and 15 have their ends beveled upwardly, as shown at 21 and 22, to fit within the beveled recesses in the clamp body. Thus, when the clamp is picked up, the expanding members are carried therewith, but the expanding members are free for transverse movement such as takes place during the expanding or clamping action. The expanding members 14 and 15 lie side by side in the recess in the lower part of the clamp body, and they are each formed on their inner faces with corresponding or aligned hemi-conical recesses 23 and 24 to receive the conical head of an expanding screw.

The embodied form of expanding means comprises a screw 25, having a conical head 26, fitting into the hemi-conical recesses formed in the expanding members, the 5 screw-threaded shank 27 of the screw engaging the screw threaded aperture 28 which extends upwardly through the clamp body 10. The end of the screw is provided with a slot 29 accessible from the top of the 10 clamp.

Means are provided, in accordance with one feature of the invention, for preventing the removal or accidental dropping out of the clamp from the slot while permitting 15 the clamp to move freely along the slot. In the embodied form of such means, a screw 30, preferably provided with a conical end or tip 31 is screw-threaded through the clamp body 10, so that the conical tip of 20 the screw is just above and in alignment with the inner faces of the expanding members 14 and 15. By turning the screw 30 home, or to the proper point, the expanding members 14 and 15 may move outwardly 25 just sufficiently to prevent the upward removal of the clamp from the slot, while leaving it free to slide longitudinally therein. By turning the screw 30 back very 30 slightly, the expanding members 14 and 15 may move inwardly, so that the clamp is readily removable from the slot.

A clamp constructed in accordance with the invention is very compact and sturdy, having the jaw and body integral, and having 35 the body of one piece filling the main cross-sectional area of the slot, and extending for the full length of the clamp structure. The expanding members are simple and strong, and are yet inclosed within and 40 protected by the clamp body, and the clamping action is very simple and direct. The clamping screw cannot come out of the clamp and cause damage to the press or plates. There is also great advantage in 45 the utilization of the headless screws, as the breaking off of the screwheads with consequent damage to the press or plates, and the screw is at all times inside of the clamp.

50 It will be understood that changes may be made from the details of construction as shown and described, within the scope of the accompanying claims, without departing from the principles of the invention and 55 without sacrificing its chief advantages.

What I claim as my invention and desire to secure by Letters Patent is:

1. A plate clamp operating with a slotted plate bed, and including in combination a 60 clamping jaw, a body integral therewith, and located within the slot in the bed plate, said body having a vertically disposed screw-threaded aperture therein and another screw-threaded aperture, said body being 65 formed with a transverse recess therein, the

end walls thereof in the body widening upwardly, two expanding members fitting within said recess longitudinally side by side and having their ends beveled to conform to the bevel of the recess in the body, 70 and having hemi-conical recesses in their inner faces, a screw threaded into the screw-threaded aperture in the clamp body and having a conical head within the hemi-conical recesses in the expanding members to 75 hold the clamp firmly in position in the slot, and a screw in said other screw-threaded aperture in the clamp body and having a conical point adapted to pass between the two expanding members to force them only 80 slightly outwardly to loosely retain the clamp in the slot.

2. A plate clamp operating with a slotted plate bed and including in combination a clamping jaw, a body integral therewith and 85 located within the slot in the bed plate, said body having a screw-threaded aperture therein and being formed with a transverse recess therein intermediate its ends, the end walls of the recess widening upwardly, two expanding members fitting within said recess longitudinally side by side and having their ends beveled to conform to the bevel of the recess in the body, and having hemi-conical recesses on their inner faces, and a 90 screw threaded into the clamp body and having a conical head within the hemi-conical recesses in the expanding members to force them outwardly into engagement with the walls of the slot. 95

3. The combination with a plate bed for printing plates having a groove therein the sides of which are undercut at the bottom and with substantially parallel sides from the undercut portion to the top, of a plate 105 clamp having a plate engaging jaw and a body extending into the slot, there being a pair of expanding members carried by the body in alignment with the undercut portion of the slot, means for forcing the expanding members outwardly into said undercut portion to firmly hold the plate clamp in position, and means for moving the expanding members out slightly to hold the clamp body loosely in the slot. 110

4. The combination with a plate bed for printing plates having a groove therein the sides of which are undercut at the bottom and with substantially parallel sides from the undercut portion to the top, of a plate 120 clamp having a plate engaging jaw and a body extending into the slot, there being a pair of expanding members carried by the body in alignment with the undercut portion of the slot, a screw threaded in the 125 body to force the expanding members forcibly into the undercut portion of the slot and a screw threaded into the clamp body to move the expanding members slightly apart to hold the clamp loosely in the slot. 130

5. A plate clamp operating with a slotted plate bed, and including in combination a plate clamping jaw, a body integral therewith and located within the slot in the bed 5 plate, oppositely moving expanding members mounted in ways in said body, and means for forcing said expanding members outwardly laterally on both sides without movement along said body to expand and 10 fasten the clamp in the slot. 75
6. A plate clamp operating with a slotted plate bed, and including in combination a plate clamping jaw, a body integral therewith and located within the slot in the bed 15 plate, said body having internal guideways substantially parallel to the surface of the plate bed, oppositely moving expansion members within the body and slideable in said guideways outwardly on both sides 20 against the slot walls, and means for forcing the expansion members outwardly to fasten the clamp in the slot. 80
7. A plate clamp operating with a slotted plate bed, and including in combination a 25 plate clamping jaw, a clamp body integral therewith and located within the slot in the bed plate, oppositely moving expanding members guided by and movable outwardly on both sides of but not along the body to 30 fasten the clamp in the slot, and means for forcing out the expanding members to fasten the clamp in the slot. 85
8. A plate clamp operating with a slotted plate bed and including in combination a 35 clamping jaw, a body integral therewith and located within the slot in the plate bed, said body having expanding members movably mounted therewithin, and a screw having threaded engagement with the clamp 40 body and having a conical bottom engaging with the expanding members to force them only transversely outwardly into engagement with the slot walls. 90
9. A plate clamp operating with a slotted 45 plate bed and including in combination a clamping jaw, a body integral therewith, oppositely moving expanding devices each having flat engaging faces gripping the slot wall on both sides of the clamp body and 50 movable thereagainst without being movable along the clamp body, and means for forcing out the expanding members to fasten the clamp in the slot. 95
10. A plate clamp operating with a slotted 55 plate bed and including in combination a clamping jaw, a body integral therewith and located within the slot in the plate bed, said body having a coöperating expanding member having a hemi-conical recess there- 60 in, and a screw threaded into the clamp body and having a conical bottom engaging the hemi-conical recess in the expanding member to force it against the clamp wall. 105
11. A plate clamp operating with a slotted 65 plate bed and including in combination a clamping jaw, a body integral therewith and located within the slot in the plate bed, said body having a recess only in the bottom 110
- clamping jaw, a body integral therewith and located within the slot in the plate bed, said body having two coöperating expanding members having hemi-conical recesses each facing the other, a screw threaded into the clamp body and having a conical bottom between the expanding members and engaging the hemi-conical recesses in the expanding members to force them outwardly against the slot wall. 115
12. A plate clamp operating with a slotted plate bed and including in combination a clamping jaw, a body integral therewith and located within the slot in the plate bed, said body having an expanding member 120 mounted within and projectable from and retractable within the clamp body and a screw threaded into the clamp body and movable upwardly relatively to the expanding member to force it horizontally against the slot wall, said screw being positionable to permit the retraction of the expanding member within the clamp body. 125
13. A plate clamp operating with a slotted plate bed and including in combination a 130 clamping jaw, a body integral therewith and located within the slot in the plate bed, said body having horizontal transverse guideways therein, an expanding member within the body and horizontally slideable along said guideways into gripping position and a single screw pushing against the expanding members and screw threaded in the clamp body for so moving the gripping member. 135
14. A plate clamp operating with a slotted plate bed and including in combination a clamping jaw, a body integral therewith and located within the slot in the plate bed, said body having transverse guideways 140 therein, an expanding member within the body and transversely movable along said guideways into gripping position and a screw threaded into the clamp body and having an enlarged bottom engaging the gripping member to move it transversely only to cause it to grip the slot wall. 145
15. A plate clamp operating with a slotted plate bed and including in combination a clamping jaw, a body integral therewith and located within the slot in the plate bed, said body having transverse guideways 150 therein, an expanding member within the body and transversely movable along said guideways into and out of gripping position and having a hemi-conical recess therein, a screw threaded into the clamp body and having a conical bottom engaging with the recess in the gripping member to force it into engagement with the slot wall. 155
16. A plate clamp operating with a slotted plate bed and including in combination a clamping jaw, a body integral therewith and located within the slot in the plate bed, said body having a recess only in the bottom 160

part thereof of less length than the clamp body, a gripping member within said recess and having a flat surface to grip the slot wall, and means for forcing said member outwardly to engage the slot wall.

17. A plate clamp operating with a slotted plate bed and including in combination a clamping jaw, a body integral therewith and located within the slot in the plate bed, said body having a recess only in the bottom part thereof of less length than the clamp body, a gripping member slidably supported at both ends within said recess and means including a vertically arranged screw threaded in the clamp body for forcing said member outwardly to engage the slot wall.

18. A plate clamp operating with a slotted plate bed and including in combination a clamping jaw, a body integral therewith and located within the slot in the plate bed, said body having a recess in the bottom part thereof of less length than the clamp body, a gripping member within said recess and a screw threaded in the clamp body movable upwardly and having an enlarged bottom engaging the gripping member for forcing said member outwardly to engage the slot wall.

19. A plate clamp in combination with a plate bed having slots therein with straight walls in the upper part thereof and undercut walls in the bottom part thereof, the plate clamp having a transversely rectangular body substantially filling the straight part of the slot and extending downwardly into the undercut part of the slot, expanding means carried by the clamp body and including a screw moving upwardly and a member thereby movable into the undercut part of the slot to hold the clamp in position in the slot.

20. A plate clamp in combination with a plate bed having slots therein with straight walls in the upper part thereof and undercut walls in the bottom part thereof, the plate clamp having a transversely rectangular body substantially filling the straight part of the slot and extending downwardly into the undercut part of the slot, expanding means carried by the clamp body and movable into the undercut part of the slot to hold the clamp in position in the slot, and means for so moving the expanding means including an upwardly moving screw having an enlarged bottom.

21. A plate clamp in combination with a plate bed having slots therein with straight walls in the upper part thereof and undercut walls in the bottom part thereof, the plate clamp having a transversely rectangular body substantially filling the straight part of the slot and extending downwardly into the undercut part of the slot, expanding means carried by the clamp body including guideways, and a plurality of members slid-

able apart therealong into the undercut part of the slot to hold the clamp in position in the slot, and screw-threaded means for so moving the expanding means.

22. A plate clamp in combination with a plate bed having slots therein with straight walls in the upper part thereof and undercut walls in the bottom part thereof, the plate clamp having a transversely rectangular body substantially filling the straight part of the slot and extending downwardly into the undercut part of the slot, expanding means carried by the clamp body including guideways, and a plurality of members slidably apart therealong into the undercut part of the slot to hold the clamp in position in the slot, and a screw threaded into the clamp body movable upwardly and having an enlarged bottom engaging the expanding means to so move said means.

23. A plate clamp operating with a slotted plate bed and including in combination a clamping jaw, a clamp body integral therewith and located within the slot in the plate bed, an expanding member mounted within the clamp body and projectable therefrom and retractable within the clamp body and having a flat clamping face engaging the slot wall, and a vertically disposed screw threaded in the clamp body and directly engaging the expanding member to move it into clamping position, said screw having turning means accessible from the top of the clamp body.

24. A plate clamp operating with a slotted plate bed and including in combination a clamping jaw, a clamp body integral therewith and located within the slot in the plate bed, opposed expanding members mounted within the clamp body and projectable from and retractable within the clamp body at the opposite sides thereof and having flat clamping faces engaging the opposite slot walls, and means for simultaneously pressing the expanding members outwardly against the slot walls.

25. A plate clamp operating with a slotted plate bed and including in combination a clamping jaw, a clamp body integral therewith and located within the slot in the plate bed, opposed expanding members mounted within the clamp body and projectable from and retractable within the clamp body at the opposite sides thereof and having flat clamping faces engaging the opposite slot walls, and a single screw threaded into the clamp body and directly engaging both expanding members to press them against the clamp wall.

26. A plate clamp operating with a plate bed having a slot rectangular in its upper part and undercut in its lower part, the plate clamp having a clamping jaw and integral therewith a clamp body extending into the undercut part of the slot, an ex-

5 pansion member mounted in the lower part of the clamp body and having a flat inclined side face adapted to fit and press against the undercut portion of the slot wall, and 5 means for horizontally moving the expansion member into clamping position.

27. A plate clamp operating with a plate bed having a slot rectangular in its upper part and undercut in its lower part, the 10 plate clamp having a clamping jaw and integral therewith a clamp body extending into the undercut part of the slot, an expansion member mounted in the lower part of the clamp body and having a flat inclined side 15 face adapted to fit and press against the undercut portion of the slot wall, and a single screw mounted in and accessible for turning from the top of the clamp body and directly engaging the expansion member 20 to move it into clamping position.

28. A plate clamp operating with a plate bed having a slot rectangular in its upper part and undercut on both sides in its lower part, the plate clamp having a clamping jaw 25 and integral therewith a clamp body extending into the under cut part of the slot, a pair of oppositely moving expanding mem-

bers mounted in the lower part of the clamp body, and having flat inclined outside faces adapted to fit against the under cut walls 30 of the slot, and means for simultaneously pressing the expansion members against the undercut part of both walls of the slot.

29. A plate clamp operating with a plate bed having a slot rectangular in its upper 35 part and undercut on both sides in its lower part, the plate clamp having a clamping jaw and integral therewith a clamp body extending into the under cut part of the slot, a pair of oppositely moving expanding 40 members mounted in the lower part of the clamp body, and having flat inclined outside faces adapted to fit against the under cut walls of the slot, and a single screw turnable from the top of the clamp body and 45 engaging directly both expansion members.

In testimony whereof I have signed my name to this specification in the presence of two subscribing witnesses.
